UNITED STATES PATENT OFFICE.

ADOLF LANZDORF, OF VIENNA, AUSTRIA-HUNGARY.

AUTOMATIC RAILWAY-COUPING.

1,107,324.

Specification of Letters Patent. Patented Aug. 18, 1914.

Application filed April 15, 1911. Serial No. 621,287.

To all whom it may concern:

Be it known that I, ADOLF LANZDORF, a subject of the Emperor of Austria-Hungary, a lieutenant of the Austrian Army, and a resident of 1 Leyserstrasse, Vienna, XIII/3, Austria-Hungary, have invented Improvements in and Relating to Automatic Railway-Couplings; and I do hereby declare the following to be a full, clear, and exact description of the invention, such as will enable others skilled in the art to which it appertains to make and use the same.

The present invention has for its object the uncoupling of any desired number or series of vehicles either by making provision for the uncoupling before the detachment of each series of vehicles or by effecting the operations in advance for all the series of the entire train, the breaking up of the train into the several series being then effected from the locomotive.

The first method of uncoupling is effected in accordance with the present invention by arranging a distributing member in the pressure train pipes by the adjustment of which distributing member the pressure effect produced by a suitable pump arranged upon or in connection with the locomotive is transmitted to the piston arranged on the vehicle which releases the vehicle coupling so that the vehicles situated behind this coupling are detached. With this method of uncoupling notwithstanding the fact that only one pipe is operative, two train pipes must be provided to permit of coupling in any position of the vehicles. For the second method of uncoupling the ends of these two train pipes are connected by a transverse pipe. When vehicles are coupled, this transverse pipe is closed by the pipe ends inserted one within the other but it remains open in the case of the vehicle which for the time being is the last of the train so that a continuous conduit extending from the locomotive to the last vehicle and through the connecting conduit of the latter back to the locomotive is provided. With this arrangement one pipe serves as the out pipe and the other as the home pipe for the pressure medium. A distributing member is inserted in each of these pipes on each vehicle. Now if for example series of one, two, three or more vehicles are to be uncoupled from the train in succession, distributing members in the return conduit of each series of vehicles are

suitably adjusted. The pressure medium thus finds its outward path open and proceeds over the last vehicle into the return conduit where the distributing member suitably adjusted in the selected vehicle directs it to the respective piston and by actuating the same detaches the first series of vehicles. By the uncoupling the connecting pipe between the out and home train pipes on the vehicle which now becomes the last of the train is opened thus causing the pressure medium to reach the next adjusted distributing member and effect the uncoupling of the next series of vehicles, and so forth. In accordance with the invention the train pipe with the distributing member can likewise be utilized as a brake pipe for the vacuum or compressed air brake. With this object the distributing members are adjustable in such a manner that the return conduit can be closed and the outward conduit be connected with the brake pipe or with the cylinder of the brake piston, so that upon exhausting the outward conduit or introducing a pressure medium into it the brake piston is actuated. The ends of the train pipe on each vehicle can also be connected with those of the heating pipe and the latter can be formed in such a manner that when two vehicles meet, the heating pipe is automatically coupled.

In the accompanying drawing Figures 1, 2 and 3 illustrate the formation of the releasing device in which for each uncoupling of a series of vehicles the preparation necessary for the uncoupling must be effected. Fig. 1 illustrates the apparatus in longitudinal section. Fig. 2 is a similar view with the distributing member adjusted, Figs. 2^a and 2^b are detail views and Fig. 3 is a diagrammatic elevation of the apparatus as a whole as viewed from the under side of the vehicle. Figs. 4 to 20 illustrate the construction of the apparatus for uncoupling the vehicles in series after the manipulations for detaching all the series of vehicles have been effected. Figs. 4 and 5 illustrate the pipe ends which are formed as buffers and comprise cylindrical slide valves. Fig. 6 shows the two buffers in the coupling position. Figs. 7 and 8^a illustrate two modified forms of buffer. Figs. 8 and 9 are detail views. Fig. 10 shows the position and connection of the pipe ends formed as buffers in rear elevation. Fig. 11 shows the same in 110

plan. Fig. 12 is an underneath plan thereof. Figs. 13 to 16 show the distributing member in four different positions. Figs. 17 and 18 show the actuating and resetting device for the distributing member. Fig. 19 shows a discharge or admission valve connected with the distributing member for the train pipe. Fig. 20 shows the coupling device for the heating pipe. Fig. 21 shows the hook and eye vehicle coupling. Fig. 22 shows a locking device for the coupling, and Fig. 23 shows the apparatus as a whole mounted on a half vehicle.

The constructional forms of the releasing device represented by way of example in the drawings are adapted for the employment of a pressure medium compressed air in particular.

In accordance with the constructional form illustrated in Figs. 1 to 3, one end of the pressure conduit 1 extending through the vehicle is widened out to form a cylindrical casing 125. This casing contains a number of plates 126 which are radially displaceable and overlap laterally; these plates are subjected to the action of springs 127 in such manner that they are pressed against the center of the casing so that they expose a conical passage 128 (Fig. 1). One of these plates is connected with a slide 129 serving to close the train pipe in an air tight manner. When the vehicles are coupled, the conically tapering pipe end 130 of the other vehicle enters the opening 128 and forces the plates 126 apart and owing to the positive connection the slide 129 is opened (Fig. 2). By this means a through train pipe is formed as far as the closed slide of the last vehicle. A three way cock 63 is mounted in the train pipe as the distributing member; by means of a branch pipe 61 it is connected with the pressure cylinder 57 of a piston 59 serving for releasing the coupling. The automatically acting vehicle coupling consisting of hook and eye 110 and 111 (Fig. 3) can be of any convenient construction.

If the coupling is to be disconnected at any part of the train, that is to say if it be desired to uncouple a number of vehicles from the train, the three way cock of the last vehicle of the series of vehicles to be uncoupled is rotated through 90° in the direction indicated by the arrow in Fig. 1. By this means the pipe proceeding from the locomotive is closed toward the rear by the adjusted cock but placed in communication with the pressure cylinder of the vehicle in question. Now if steam or compressed air be despatched from the locomotive into the train pipe it finds the pipe closed by the three way cock and is conducted through the conduit 61 to the pressure cylinder 57 where it forces the piston 59 forward, thereby uncoupling the vehicles, either by means

of direct shock on the coupling or by means of lever mechanism 131 (Fig. 3).

When the series of vehicles is uncoupled the conically formed end 130 of the detached vehicle withdraws from the widened pipe end 125 of the last vehicle remaining on the train whereby the slide 129 of this last vehicle is closed. The conical pipe ends are provided toward the end, as shown in Figs. 2^a and 2^b, with fluting 130' so that during the separation of the pipe-coupling the pressure medium, in the trainpipe, can escape before the pipe is closed by means of the slide.

In order to be able to use the apparatus described above when the vehicle is reversed, as shown in Fig. 3 two similarly formed conduits 1 and 2 are provided so that according as the locomotive is situated on one or other side of the vehicle one or other of these conduits can be used. The other constructional form of the releasing device is as follows: As shown in Fig. 23 the ends of the two train pipes 1 and 2 extending throughout the vehicle are formed as buffers 3 and 4 which, if desired, can serve to replace the buffers heretofore usually employed. The buffer plate 5 (Fig. 4) of one pipe end is formed with a hopper-shaped recess 6 while the plate of the other, that is to say the adjacent pipe end comprises a conical projection 7 (Fig. 5) exactly fitting the cavity 6 in the first buffer plate, a gradually tapering tubular projection 8 connecting with this projection 7. Behind the buffer plate the pipe ends are formed as a cylindrical casing 9 inclosing the buffer spring and a cylindrical slide valve subjected to the influence of this spring. The casing 9 of the buffer-shaped buffer (Fig. 4) is closed at its rear end by a cap 10 which comprises a hollow cylindrical extension 11 closed at its end. In this extension a cylindrical slide valve 12 is slidably arranged being pressed against the buffer plate by the spring 14 bearing on a flange 13 of the slide. By means of a front annular extension 15 the slide engages in an annular groove in a packing piston 16 movably mounted in the casing, the movement of this piston being limited by the end wall of the casing and by the pin 17. The piston is conically bored for the passage of the tubular projection 8; for the purpose of closing the pipe in an air-tight manner a conically shaped sleeve 18, resilient toward its periphery, is inserted in this bore and secured to the piston by a screw cap 19. The resiliency of the sleeve is obtained owing to the fact that it is provided with incisions proceeding alternately from either side and alternately overlapping (Fig. 9). These incisions can be rectilinear, or as shown in Fig. 9 in broken lines, they may run helically. Between the sleeve and the piston an

interval is left and filled with a suitable packing material 21 preferably Jenkin or the like. Owing to the resilient formation of the sleeve in combination with the packing material a packing zone running zig-zag peripherally is provided and packs the entering tubular projection 8 of the other buffer. The slide casing 11 comprises two openings 22, 23 while the cylindrical slide valve 12 is provided with a passage 24.

Fig. 7 illustrates a different construction as regards the connection of the cylindrical slide valve with the piston; this construction differs from that described above only owing to the fact that the tubular extension 15 of the slide valve does not engage in an annular groove in the piston but between the piston and the wall of the casing.

The buffer furnished with the tubular extension 8 is formed similarly to the buffer described above. Here the cylindrical slide valve 25 forms one piece with the buffer plate 5 as the slide valve projects into the valve slide casing 26 as an extension of the tubular projection from the plate. The spring casing 27 is screwed on to the casing, its spring 14 pressing on a sleeve 28 of the buffer plate which extends between the valve casing and the spring casing. By means of screws 29 a limited movement of the buffer and of the cylindrical slide is produced in one direction and an elastic movement in the other direction is produced by the springing.

Fig. 8 illustrates a simpler mode of construction which consists in omitting the spring casing 27, and arranging the spring 14 in the space 30 formed by the cylindrical valve 25, 28 and the valve casing 26. One end of the spring 14 rests upon the valve casing, its other end presses against the cylindrical valve the movements of which are limited by a flange 28' which comes into contact with the shoulder 26' of the cylindrical valve. The slide valve casing and the cylindrical slide valve are provided with openings 22, 23 and 24 in a similar manner to the buffer described above. In the forward position of the slide valve the openings 22, 23 in the casing are opened, but the opening 24 in the slide is covered. In the rear position of the slide the opening 24 registers with the opening 22 and the opening 23 in the casing is closed. The openings 22 of the two slide casings communicate by means of flexible connections 31 (Fig. 23) with the two rigid train pipes 1 and 2 fixed in the middle of the frame, while on the openings 23 is fitted a pipe 32 connecting the two train pipes respectively to the slide valve casing of the buffers lying side by side (Fig. 10). Consequently a similarly formed conduit proceeds under the vehicle from both ends of the vehicle, this conduit being connected at the end of the train with the other train pipe. Now if two vehicles provided

with this apparatus meet, the cylindrical slide valve 25 of the buffer 4 provided with the tubular projection 8 is pushed back into its end position (Fig. 6) while the cylindrical slide valve 12 of the hopper-shaped buffer 70 3 is forced back into its rear end position by the tubular projection 8 of the opposite buffer 4. By this means the transverse connection between the slide valve casings of the two opposite pairs of buffers is broken, 75 but the continuous connection of the two conduits of the vehicle is established by the intermediary of the two oppositely situated cylindrical slide valves which are opened by the collision, while in the case of the 80 rear pair of buffers of the colliding vehicle, as the slide valves of these buffers remain unaffected, communication from one train pipe to the other is maintained. Accordingly when any number of vehicles are coupled a pneumatic train pipe is formed which leads from the locomotive to the last vehicle and thence back to the locomotive. In order, however, that the cylindrical slide valves may remain in the position resulting 85 from the collision and the train pipe connection thereby effected be maintained, the buffers are provided with a hook coupling by means of which the two buffers are held together and which is released simultaneously with the vehicle coupling by compressed air. The coupling consists of two-armed levers 34, 35 (Fig. 12) arranged on the under side of the spring casing and rotatable about pivots 33 (Figs. 4 and 5) the 100 lower lever located on the buffer 4 being formed as a hook which is opposite a passage 36 in the buffer. When the buffers meet, the hook passes through the opening 36 and an opening 37 provided on the other 105 buffer 3 and engages over its rear edge. The lever 36 of the other buffer ends in a rod which in the coupling position is situated opposite the hook on the other vehicle and serves for releasing it, (Fig. 12). Each of 110 the other ends of the levers are connected with a piston of a pressure cylinder which pistons release the levers. The pressure cylinder 38, which is arranged in the plane of the levers, contains the piston 39, 40 between which a space 41 is left free for the introduction of the compressed air. The piston rods 42 are provided with shoes 43 subjected to the influence of springs 44. One end of the springs bears against the end 115 wall of the bushing while at the other end they press against the flange 45 of the shoes. These shoes are jointed to the levers. By means of this arrangement of springs the result is attained that if the rotation of the 120 levers occurs when the buffers meet, only the shoes are displaced while the pistons remain unaffected. The pressure cylinder is connected by a tubular part 56, proceeding from the space or chamber 41, with a second pres- 125 130

sure cylinder 57, whose piston 59 or piston rod 60 (subjected to the action of a spring 58) serves for releasing the vehicle coupling.

The operation of the releasing device is as follows: If compressed air proceeds from the locomotive through the train pipe 61 into the front pressure cylinder 38, the pistons 39, 40 are forced apart against the action of the springs 44 and the two levers 34, 35 are thereby rotated. By this means one hook lever is disengaged from the buffers while the other lever releases the hook lever 34 of the opposite vehicle. Simultaneously the piston 59 of the other pressure cylinder 57 is forced forward, its rod 60 striking against the vehicle coupling and releasing it. If the pressure is relieved all the parts return to their normal position under the influence of the springs 44, 58. The conduit 61 serving for the supply of compressed air proceeds from a rotary slide valve. A valve of this kind is inserted in each of the two pipes 1 and 2 and after it has been adjusted deflects the compressed air from the main pipe to the pressure cylinders. The rotary slide valve consists of a solid cylinder 63 packed in a bushing 62 (Figs. 13 to 16) comprising in the manner of the three way cock a radial bore 64 and a passage 65 branching from this bore. In the normal position of the valve illustrated in Fig. 13 the continuous connection of the pipe 1 or 2 is established by the passage 64. If, however, the slide is rotated through 90° in a contra-clockwise direction (Fig. 14) the continuous conduit is interrupted and connection established between this conduit and the conduit 61 proceeding to the pressure cylinder 38, 57. It is therefore obvious that, as in the construction previously described, any desired number of vehicles can be simultaneously detached from the locomotive after the slide valve located on the vehicle immediately following the number of vehicles to be uncoupled has been adjusted. In order, however, to permit of uncoupling a number of series of vehicles from the locomotive, after the various slide valves have previously been adjusted, the slide valves in the return conduit of the vehicle in question must be adjusted; it is likewise necessary that after a series of vehicles has been uncoupled, the slide valve should automatically be returned to the normal position so that a conduit is provided to the next adjusted slide valve. This object is obtained in the following way: The prolonged spindle 66 (Figs. 17 and 18) of the rotary slide valve is mounted in the side wall of the vehicle frame 67 and carries a toothed wheel 68 which meshes in the lower toothed end of a rod 69 while in the other upper toothed end of the rod a second toothed wheel 70 engages. Upon the shaft 71 of this toothed wheel an arm 73 loaded with a weight 72 and serving as a handle is

secured. The arm comprises a joint 24 in such a manner that it can be turned over in its direction of rotation. If the slide valve is to be adjusted, the weighted arm is rocked toward the rearward vehicle through 90° and the weight is suspended in a fork 75 provided on the vehicle as shown in Fig. 17 in broken lines. Owing to the transmission of the movement by means of the rack 69 and the toothed wheels 68, 70, the valve is rotated in the manner described. Now if for example two, five, ten and so forth vehicles are to be disconnected from a train, the weights are arranged in the shunting direction, that is to say rearward, by the shunters beginning from the end of the train, in such a manner that the series of vehicles to be uncoupled are situated between the raised weights. After this everything is attended to from the locomotive, that is to say, automatically. The compressed air flowing in encounters an open outward pipe, passes over the last vehicle into the return pipe where it is deflected in the rotary slide valve 63 of the vehicle next to the end of the train into the pressure cylinder 38, 57 and uncouples the first series of vehicles. When the train is divided, the weighted arm 73, hinged to the last vehicle of the remaining train-division and having rested upon the support 75 of the adjoining and first vehicles of the detached division, drops, and by the rotation of its shaft 71 and the agency of the toothed wheel 70, the rack 69, and the toothed wheel 68 mounted on the axle 66 of the rotary slide valve, the rotary slide valve is returned to its normal position *i. e.* the shut-off-position. Now as owing to the retractive movement of the cylindrical slide valves 12, 25 in the buffers of the vehicle which has now become the last vehicle of the train, connection is again established between the two main pipes 1 and 2 and a passage to the return pipe has been formed through the rotary slide valve of this vehicle, the compressed air reaches the next adjusted rotary slide valve and uncouples the next series of vehicles. This operation is repeated for every adjusted rotary slide valve. In this connection it should be noted that in the first place the compressed air flowing in acts on the piston 16 forced rearward by the collision and as shown by arrows in Fig. 6 presses it onto the conical tubular projection 8 of the entering buffer.

In order to produce pressure on the outer annular face with the form of piston illustrated in Fig. 4, passages 76 can be provided in the oppositely located cylindrical slide valve to permit the compressed air to reach the outer annular surface so that it is able to press upon the whole of the end face of the piston. In order that, with the stepwise uncoupling of the series of vehicles, when the first series has been uncoupled the next

series may not become unintentionally uncoupled by the compressed air remaining, it is necessary to reduce the pressure in the remaining conduit or to destroy it altogether. In order to attain this result an exhaust 77 (Fig. 19) is inserted in the main pipe 1 or 2 and this valve is operated by the fall of the weighted lever when a series of vehicles is detached. With this object a 10 plate 79 comprising a spring arm 78 is mounted on the spindle 66 of the rotary slide valve 63 directly beside the latter. The end of a lever arm 81 connected with the valve rod 80 extends within reach of the 15 rotary path of this spring arm so that when the plate is rotated by the falling weighted lever the arm 81 is raised and the valve thereby opened.

As already stated with the assistance of 20 the rotary slide valves the continuous conduit can also be employed for actuating the compressed air brake. This is effected in the following manner: The rotary slide valve comprises an axial bore 82 (Figs. 13 25 to 16) which in the normal position and in the position for the uncoupling of the vehicle is covered by the end walls of the bushing 62. If, however, the rotary slide valve is rotated through 90° in a clockwise direction, the bore 82 comes between a pipe 83 proceeding from the other train pipe 1 or 2 and opening into the bushing (Figs. 15, 16 30 and 24) and a pipe 85 leading to the brake cylinder 84, while the conduit in which the 35 rotary slide valve is situated is cut off. By this adjustment of the rotary slide valve communication is established between the adjacent length of pipe 1 or 2 and the brake cylinder. Now if before the departure of a 40 train the rotary slide valve 63 of the several vehicles, that is to say, the valves in the return pipe are adjusted in the manner already described with the weighted lever rotated toward the locomotive and suspended in a 45 rack 86 provided on the vehicle (Fig. 18) when compressed air is admitted to the pipe all the vehicles will be simultaneously braked.

In the normal position and also in the two 50 end positions the weighted lever 73 is automatically secured by a ratchet wheel 87 mounted on the shaft 71 of the gear wheel 70 (Figs. 17, 18) a spring locking pawl 88 engaging in this ratchet wheel. In order to 55 effect automatic coupling of the heating pipe simultaneously with the coupling of vehicles or series of vehicles, the heating pipes 89, 90 on both sides of the vehicle (Fig. 23) are carried to the buffer plates and the ends are 60 formed similarly to the ends of the pressure pipe for the purpose of obtaining a good joint. With this object one pipe passes through the plate 5 of one buffer, preferably that comprising the tubular projections 8, 65 and ends in a conical projection 91 from the

front of the buffer (Fig. 20) while the other buffer comprises an opening 92 corresponding with the tubular projection. This opening is covered by a bushing 93 with which the conduit 89 of the other vehicle connects. 70 As is the case in the hopper-shaped buffer, a packing piston 95 provided with resilient tubular insertion 94 is displaceably arranged in the bushing. When the buffers come together, the tubular projection 91 of one 75 buffer enters the conical opening of the piston of the other buffer, whereby the two pipes are coupled together. By the pressure exerted on the end face of the piston by the steam flowing toward the tubular projection 80 the piston is pressed against the projection, thereby forming a good joint between the two pipes at the coupling place. In order, however, that the good joint between the pipe ends both of the pressure 85 conduit and of the heating conduit may not be impaired or entirely destroyed by the jolting of the vehicles during running, the buffers are rockably mounted by means of the springs 96 (Fig. 10). The springs are 90 mounted on a third buffer 97 arranged between the other two buffers and its ends engage sockets 98 in which the buffers are mounted so as to be displaceable axially. This arrangement enables the buffers to rock 95 both vertically and horizontally, independently of the vehicle, while relative displacement during negotiating curves is rendered possible owing to the fact that the pipe 32 (Fig. 10) connecting the two buffer casings 100 11, 26 is secured to the former by means of screw-caps 99 so that the pipe is able to rotate at the fixing places during relative displacement of the casings. The two buffer casings are connected by a web 100 in such 105 a manner that the web embraces the rear ends of the slide valve casings by means of eyes and is held by nuts 101, convex on their inner side screwed on to the casings. Arms 102 of a piston rod 104 subjected to the 110 action of the spring 103 of the buffer 97 engage these webs. This buffer 97 serves to absorb the remaining shock after the coupling of the two buffers. 115 If the two buffers of the train pipe meet, the first shock is absorbed by them until they are coupled one with the other so that no further yielding is possible. The coupled buffers which thus constitute a rigid system owing to the fact that they are able 120 to slide in the sockets 98 transmit the remaining shock into the spring 103 of the buffer 97 by the intermediary of the web 100 and of the piston 105, this spring completing its absorption. The spring bears against 125 a plate 105 which is connected with the piston rod by means of a ball joint 106 in order to insure the mobility of the whole of the buffer system. The plate is provided with studs 107 on both sides and these studs pass 130

through slots in the buffer casing. The forked ends of the draw bar 108 arranged beneath the vehicle engage these studs; this rod is connected in the known manner with 5 a traction device inside the frame. By means of this arrangement a through connection of the draw bars is established by means of the buffers. The studs 107 are embraced by slots in the fork ends, in such a 10 manner that on starting the draw bars are displaced while in the recoil of the buffers the bar remains unaffected.

In the present case the coupling consists of an eye 110 mounted on the shaft 109 15 and inclined forward, and of a rotatable hook 111 jointed thereto. The jointing of these two parts is effected owing to the fact that the bent arm 112 of the eye engages by means of a stud 115 an arm 114 secured to the shaft 113 of the hook and likewise 20 located at an angle to the hook. By this means the hook is obliged to effect a corresponding movement when the eye moves and vice versa. The hook is formed with a slot 25 116 through which the shaft 113 which is made quadrangular at this place passes so that the hook is displaced by the shaft but is able to move longitudinally. A slide member 117 (Fig. 22) is arranged in the 30 hook; it is subjected to the action of a spring 118 which tends to press the slide member backward. The slide member comprises at its front end a projection 119 which is guided in a recess 120 in the hook and 35 projects somewhat onto the attaching face of the hook. The rear end of the hook is formed as a bolt 121 which comes opposite the lower edge of the vehicle frame 67. A two-armed lever 122 is arranged in a recess 40 125 in the hook; this lever is mounted on the shaft 113 which at this place is cylindrically formed. One arm of the lever engages through a recess 123 in the slide member, while the other arm is connected with 45 the hook by a link 124. When two vehicles provided with this coupling meet, the eye of one vehicle engages the hook of the other vehicle. The lever arm of the eye then presses the arm of the hook forward and 50 causes the hook to rotate downward until, finally, the over-weighted eye of one vehicle falls in whereby the vehicles are coupled. On starting, the eye of the other vehicle acts on the projecting part of the slide member 55 which it draws forward. By this means owing to the transmission of movement of the lever and link in the opposite direction the hook is pressed backward and engages beneath the breast of the vehicle by 60 means of a bolt, thereby locking the coupling. Owing to the displacement of the hook it is shortened so that simultaneously with the locking of the coupling the vehicles are automatically brought closer together. 65 This coupling is detached by the piston rod

60 of the pressure cylinder which projects in the other side of the breast of the vehicle striking against the lever arm 112 of the eye.

What I claim as my invention and desire 70 to secure by Letters Patent is:

1. An automatic railway coupling comprising in combination with coupling means and operating mechanism connecting the train line circuits with said coupling means 75 so as to operate the same, two conduits extending the whole length of the vehicle, pipes connecting said two conduits with each other toward both ends of said vehicle, a distributing member interposed in each of said conduits and located on each vehicle, a relief valve in each of said conduits, means for automatically operating said relief valve when the vehicle upon which it is carried is uncoupled, cylindrical slide valves connected 80 with the ends of both of said conduits, said cylindrical slide valves being adapted when the vehicles are coupled up to interrupt communication between the two conduits through said valves and to establish a through connection between all the conduits on all of the vehicles. 85

2. An automatic railway coupling comprising in combination with coupling means and operating mechanism connecting the 90 train line circuits with said coupling means so as to operate the same, a source of compressed fluid, two conduits extending the entire length of the vehicle and connected with said source of fluid, a coupling device, means 100 for operating said device, connections from said conduits to said operating means, pipes connecting said two conduits with each other toward the ends of said vehicle, a distributing member interposed in each of said 105 conduits and located on each vehicle, a relief valve in each of said conduits upon each vehicle, means for automatically operating said relief valve when the vehicle upon which it is carried is uncoupled, cylindrical 110 slide valves connected with the ends of the said conduits, said cylindrical slide valves being adapted when the vehicles are coupled to interrupt communication between the two conduits and to establish a through connection between the conduits on all the vehicles, and springs for reestablishing communication between the conduits on each side of the train when the vehicles are uncoupled. 115

3. An automatic railway coupling comprising in combination with coupling means and operating mechanism connecting the train line circuits with said coupling means so as to operate the same, two conduits extending the whole length of the vehicle, 120 pipes connecting said two conduits with each other toward both ends of said vehicle, a distributing member interposed in each of said conduits and located on each vehicle, a relief valve in each of said conduits, means 125

for automatically operating said relief valve when the vehicle upon which it is carried is uncoupled, cylindrical slide valves connected with the ends of both of said conduits, 5 said slide valve on one conduit at one end of the vehicle being formed into a tapering portion, a member having a flared opening adapted to receive one of such conically tapering portions, said member being connected with the said slide valve on the same conduit at the other end of the vehicle, a packing ring located in said member, and a 10 spring engaging each of said cylindrical slide valves and adapted to reestablish communication between said two conduits 15 through said slide valves on the uncoupling of the vehicle.

4. An automatic railway coupling comprising in combination with coupling means and operating mechanism connecting the train line circuits with said coupling means so as to operate the same, two conduits extending the whole length of the vehicle, pipes connecting said two conduits with each other toward both ends of said vehicle, a distributing member interposed in each of said conduits and located on each vehicle, a relief valve in each of said conduits, means for automatically operating said relief valve 20 when the vehicle upon which it is carried is uncoupled, cylindrical slide valves connected with the ends of both of said conduits, said slide valve on one conduit at one end of the vehicle being formed into a tapering portion, a member having a flared opening adapted to receive one of such conically tapering portions, said member being connected with the said slide valve on the same conduit at the other end of the vehicle, a 25 packing ring located in said member, a spring engaging each of said cylindrical slide valves and adapted to reestablish communication between said two conduits through said slide valves on the uncoupling 30 of the vehicle, a casing surrounding each of said cylindrical slide valves, a buffer member formed at the extremity of said casing, hooked levers for connecting the meeting buffers of two vehicles together, a cylinder, a piston working therein, piston rods, a movable shoe upon each of said piston rods, a spring surrounding each of said shoes, and connections from said shoes to the said hooked levers, substantially as described. 35

6. An automatic railway coupling comprising in combination with coupling means and operating mechanism connecting the train line circuits with said coupling means so as to operate the same, two conduits extending the whole length of the vehicle, pipes connecting said two conduits with each other toward both ends of said vehicle, a distributing member interposed in each of said conduits and located on each vehicle, a relief valve in each of said conduits, means for automatically operating said relief valve 40 when the vehicle upon which it is carried is uncoupled, cylindrical slide valves connected with the ends of both of said conduits, said slide valve on one conduit at one end of the vehicle being formed into a tapering portion, a member having a flared opening adapted to receive one of such conically tapering portions, said member being connected with the said slide valve on the same conduit at the other end of the vehicle, a 45 packing ring located in said member, a spring engaging each of said cylindrical slide valves and adapted to reestablish communication between said two conduits through said slide valves on the uncoupling 50 of the vehicle, a casing surrounding each of said cylindrical slide valves, a buffer member formed at the extremity of said casing, hooked levers for connecting the meeting buffers of two vehicles together, a cylinder, a piston working therein, a connection for said piston to each of said levers for releasing the levers, and means for admitting compressed fluid to said cylinder. 55

5. An automatic railway coupling comprising in combination with coupling means and operating mechanism connecting the train line circuits with said coupling means so as to operate the same, two conduits extending the whole length of the vehicle, pipes 60 connecting said two conduits with each other toward both ends of said vehicle, a distributing member interposed in each of said conduits and located on each vehicle, a relief valve in each of said conduits, means for automatically operating said relief valve 65

when the vehicle upon which it is carried is uncoupled, cylindrical slide valves connected with the ends of both of said conduits, said slide valve on one conduit at one end of the vehicle being formed into a tapering portion, a member having a flared opening adapted to receive one of such conically tapering portions, said member being connected with the said slide valve on the same conduit at the other end of the vehicle, a packing ring located in said member, a spring engaging each of said cylindrical slide valves and adapted to reestablish communication between said two conduits through said slide valve on the uncoupling of the vehicle, a casing surrounding each of said cylindrical slide valves, a buffer member formed at the extremity of said casing, hooked levers for connecting the meeting buffers of two vehicles together, a cylinder, a piston working therein, piston rods, a movable shoe upon each of said piston rods, a spring surrounding each of said shoes, and connections from said shoes to the said hooked levers, substantially as described. 90

6. An automatic railway coupling comprising in combination with coupling means and operating mechanism connecting the train line circuits with said coupling means so as to operate the same, two conduits extending the whole length of the vehicle, pipes connecting said two conduits with each other toward both ends of said vehicle, a distributing member interposed in each of said conduits and located on each vehicle, a relief valve in each of said conduits, means for automatically operating said relief valve when the vehicle upon which it is carried is uncoupled, cylindrical slide valves connected with the ends of both of said conduits, said slide valve on one conduit at one end of the vehicle being formed into a tapering portion, a member having a flared opening adapted to receive one of such conically tapering portions, said member being connected with the said slide valve on the same conduit at the other end of the vehicle, a 95 conically formed resilient sleeve arranged within said member, said sleeve being provided with incisions extending alternately on each side and serving to insure a tight joint with the conically tapering portions projecting into said member, and a spring engaging each of said cylindrical slide valves and adapted to reestablish communication between said two conduits through said slide valve on the uncoupling of the vehicle. 100

7. An automatic railway coupling comprising in combination with coupling means and operating mechanism connecting the train line circuits with said coupling means so as to operate the same, two conduits extending the whole length of the vehicle and communicating with each other at the ends, 105

distributing members interposed in said conduits and located on said vehicle, an automatically opening valve in said conduits, cylindrical slide valves connected with the 5 ends of the said conduits and adapted when the vehicles are coupled up to interrupt communication between the two conduits and to establish a through connection between all the conduits of all the vehicles, springs acting 10 on said slide valves for reestablishing communication between the conduits on each side of any particular vehicle when same is uncoupled, the ends of said pipe being extended in the form of buffers having the 15 shape of slide valves, the slide valve on the conduit on one side of the vehicle tapering forward and the other one recessed in which a packing ring is displaceably arranged and into which a conically formed resilient 20 sleeve is arranged, said sleeve being provided with incisions extending alternately on each side for the purpose of obtaining a good joint, hooked levers for coupling said buffers together, and a member connected 25 therewith and with a piston moving in a cylinder for releasing said hooked levers.

8. An automatic railway coupling comprising in combination with coupling means and operating mechanism connecting the 30 train line circuits with said coupling means so as to operate the same, two conduits extending the whole length of the vehicle and communicating with each other at the ends, distributing members interposed in said conduits and located on said vehicle, an automatically 35 opening valve in said conduits, cylindrical slide valves connected with the ends of the said conduits and adapted when the vehicles are coupled up to interrupt communication between the two conduits 40 and to establish a through connection between all the conduits of all of the vehicles, springs acting on said slide valves for reestablishing communication between the conduits on each side of any particular vehicle when same is uncoupled, the ends of said pipes being extended in the form of buffers having the shape of slide valves, the slide valve on the conduit on one side of the vehicle tapering forward and the other one recessed in which a packing ring is displaceably 45 arranged and into which a conically formed resilient sleeve is arranged said sleeve being provided with incisions extending alternately on each side for the purpose of obtaining a good joint, hooked levers for coupling said buffers together, a member pivotally connected therewith and with shoes of piston rods located in cylinders for releasing 50 the hooked levers from the buffers and springs acting in opposition to outward movement of said pistons for locking the buffers of the vehicles together.

9. A railway coupling comprising in combination with coupling means and operating

mechanism connecting the train line circuits with said coupling means so as to operate the same, two conduits, a source of fluid pressure connected therewith, pipes connecting said conduits toward the end of each 70 vehicle, a distributing member interposed in each of said conduits upon each vehicle, slide valves connected with the ends of said conduits, a casing for each of said valves, buffer members formed by each of said casings, a 75 shock absorber arranged between said casings, and connections from each of said valves to said shock absorber whereby some of the shock incident to the coupling operation can be transmitted to said shock absorber, substantially as described.

10. A railway coupling comprising in combination with coupling means and operating mechanism connecting the train line circuits with said coupling means so as to operate the same, two conduits, a source of fluid pressure connected therewith, pipes connecting said conduits toward the end of each vehicle, a distributing member interposed in each of said conduits upon each vehicle, slide valves connected with the ends of said conduits, a casing for each of said valves, buffer members formed by each of said casings, a resilient mounting for said buffer members, comprising a cylinder arranged between said casings, a piston within said cylinder, a spring resisting the inward movement of said piston, a universal joint in said piston, connections from said joint to the valve casings, projections from 90 said piston extending through the cylinder, and links connected to said projections.

11. An automatic railway coupling comprising a source of fluid pressure, two conduits connected therewith and extending 105 throughout the length of the vehicle, coupling devices, pressure cylinders for operating said coupling devices, a distributing member interposed in each of said conduits upon each vehicle, said distributing member comprising a rotary valve with passages therethrough adapted to maintain communication throughout the length of conduit and when operated to lead fluid into the cylinders for the operation of the coupling device, substantially as described.

12. An automatic railway coupling comprising in combination with coupling means and operating mechanism connecting the train line circuits with said coupling means so as to operate the same, a source of fluid under pressure, two conduits connected therewith and extending throughout the length of the train, and a distributing member interposed in each of said conduits upon each vehicle, said distributing member comprising a rotary valve formed with passages therethrough, a spindle for said rotary valve, and means for locking said spindle against rotation.

13. An automatic railway coupling comprising in combination with coupling means and operating mechanism connecting the train line circuits with said coupling means
5 so as to operate the same, a source of fluid under pressure, two conduits connected therewith and extending throughout the length of the train, and a distributing member interposed in each of said conduits upon
10 each vehicle, said distributing member comprising a rotary valve formed with passages therethrough, a spindle for said rotary valve and means for locking said spindle against rotation, a weighted lever for returning said
15 rotary valve to its original position upon the uncoupling of the vehicle, a resilient arm on said valve spindle, a valve in each conduit, and a projection from said valve adapted to be engaged by said resilient arm to cause the temporary opening of said valve, substantially as described. 20

In testimony whereof I have signed my name to this specification in the presence of two subscribing witnesses.

ADOLF LANZDORF.
